(57) CLAIM

The ornamental design of a glass window with an arc-shaped munin, as shown and described.

DESCRIPTION

FIG. 1 illustrates a window with an arc-shaped munin, such as could be placed on the left side of a room or wall.

FIG. 2 illustrates a second embodiment of a window with an arc-shaped munin, such as could be placed on the right side of a room or wall; and,

FIG. 3 illustrates left and right widows with arc-shaped munins positioned on an exterior wall, such that the arc-shaped munins together trace a portion of a two-centered (gothic) arch or a one-centered (semi-circular) arch. The broken lines in the drawings depict environmental subject matter only and form no part of the claimed design.
